(57) **CLAIM**

The ornamental design for a bracket assembly, as shown and described.

DESCRIPTION

FIG. 1 is a perspective view from the top, front, right of a first embodiment of the bracket assembly of my new design; FIG. 2 is a top plan view thereof, the bottom plan view being the mirror image;

FIG. 3 is an elevational view thereof from the front, the elevational view from the rear, left and right being identical; FIG. 4 is a perspective view from the top, front, right of a second embodiment of the bracket assembly of my new design;

FIG. 5 is a top plan view thereof, the bottom plan view being the mirror image of FIG. 2; and,

FIG. 6 is an elevational view thereof from the front, the elevational view from the rear, left and right being identical. The broken lines shown in the figures illustrate environmental subject matter and portions of the bracket assembly that form no part of the claimed design.
